UNITED STATES PATENT OFFICE

LEWIS A. RITES, OF GREY COURT, NEW YORK.

IMPROVEMENT IN DEVICES FOR INCREASING TRACTION OF LOCOMOTIVES.

Specification forming part of Letters Patent No. **159,453**, dated February 2, 1875; application filed November 28, 1874.

To all whom it may concern:

Be it known that I, LEWIS A. RITES, of Grey Court, in the county of Orange and State of New York, have invented a certain new and useful Improvement in the Method and Means of Increasing the Traction of Locomotive-Engines; and I do hereby declare the following to be a full, clear, and exact description of the invention, such as will enable others skilled in the art to which it pertains to make and use it, reference being had to the accompanying drawings, which form part of this specification, in which—

Figure 1 is a side view, and Fig. 2 a bottom view, of my invention.

This invention has relation to the means for increasing the traction of locomotive-engines when ascending grades, by imposing thereon the weight of the tank following; and it consists in the combination, with an elbow-lever connecting the power on the engine with the tank, of a pivoted arm, to which said lever is fulcrumed, as hereinafter described and claimed.

Referring to the accompanying drawings, A designates a steam-cylinder of any required dimension and stroke, located in the rear of the fire-box B of the locomotive-engine. C is the piston-rod, attached to a head, D, working between guides E, projecting horizontally from the cylinder-head. F designates an L-shaped lever, pivoted at its elbow to a horizontal arm, F', which is pivoted to the tank, and provided with lugs G G, to receive said

elbow. The depending arm of the lever is bifurcated for the passage of the piston-rod, to which it is secured by a transverse pin. The horizontal arm extends underneath the tank, and passes through a stirrup, e.

Steam is admitted to the cylinder in any convenient way, and when it is desired to increase the traction of the engine the steam is let into the cylinder behind the piston, which, being propelled, elevates the tank from its springs upon the lever F, and thus throws a pressure equivalent to the power applied upon the engine-wheels. The boiler-pressure is, of course, sufficient to keep the piston in position. The tank is let down by turning off the steam-pressure from the back of the piston, and exhausting the cylinder.

If necessary, steam may be employed in front of the piston to propel it back.

The object in pivoting the arm F' to the tank is to allow the lever to swing laterally, and correspond with the relative movements of the engine and tank.

Having described my invention, I claim—

The pivoted arm F', in combination with the elbow-lever F, substantially as and for the purpose set forth.

In testimony that I claim the foregoing I have hereunto set my hand this 31st day of October, 1874.

LEWIS A. RITES.
